1

My invention relates to cycle bells of the kind described in my U. S. patent application filed February 26, 1946, Serial No. 650,211. In such cycle bells there is provided a pair of opposed sounding domes with corresponding resiliently carried strikers, while means are provided to successively move each of said strikers from the corresponding dome and then to release the same, such means being formed of a reciprocatable spring-loaded lever adapted for manual actuation.

A first object of this invention is to provide a cycle bell of the above-described character wherein the means to actuate the strikers are adapted to be frictionally driven by the cycle wheel.

A further object of my invention is a cycle bell of the two dome type comprising a rotatable plate disposed within one of the sounding domes, the said plate carrying one or several projections adapted to actuate the strikers and being driven by a pinion carried by a shaft projecting from the domes and carrying a frictional roller adapted to bear against a tyre of the cycle.

In the annexed drawing:

Fig. 1 is a side view of my improved bell with parts in axial section.

Fig. 2 is an elevation thereof, the first dome being supposedly removed.

The improved bell comprises a movable support *a* pivoted at *b* on a collar *c* fixed to the cycle frame *d*. Support *a* is actuated by a cable and sheath transmission *e* against the action of a spring *b*. Under the action of the transmission *e* the frictional driving roller *f* is laterally pressed against the tyre *x*.

Support *a* is formed with an arm *a*₁ which carries the inner sounding dome *g*, the latter being clamped between the said arm *a*₁ and a shoulder formed on an axial gudgeon *h* riveted on arm *a*₁.

On gudgeon *h* there is rotatably mounted a perforated plate *i* combined with a three-armed member *j* which plays the role of a hub for the said plate *i*. As illustrated the end of the arms of member *j* are engaged through openings of plate *i* and fixed therein.

Plate *i* is provided with perforations *i*₁ along its periphery which cooperate with the teeth of a driving pinion *k* formed on a shaft *m* disposed at about 90° with respect to gudgeon *h*. Shaft *m* passes through a hole provided in the inner dome *g*; it is rotatably supported by a bearing *l* carried by the upper end of arm *a*₁; and it carries at its upper end the frictional roller *f*.

The strikers *o* are supported by short helicoidal springs *p* carried by a two-armed lever *q* mounted

on gudgeon *h*. The outer dome *r* is carried by an axial blind sleeve *r*₁ which is screwed on the projecting end of gudgeon *h*. It will be noted that each striker *o* is adapted for cooperation with one dome only.

Plate *i* is formed with a lateral projection *i*₂ adapted to pass between each striker and the corresponding dome and to move the striker inwardly against the action of its supporting spring.

It will be easily understood that when roller *f* is in frictional engagement with the tyre *x*, plate *i* is rotated, whereby projection *i*₂ displaces the strikers *o* in succession and then releases the same. The sounding domes being adapted to give two different notes, the sound produced comprises an alternate succession of these two notes.

I claim:

1. A cycle bell comprising a support; a gudgeon fixed on said support; a first sounding dome fixed to said support coaxially to said gudgeon, said dome opening opposite to said support; a member rotatably mounted on said gudgeon within said dome; means to rotate said member, said means embodying a frictional roller rotatably carried by said support and adapted to bear on a cycle tyre; a second sounding dome carried by said gudgeon coaxially to said first dome, in opposed relation thereto; strikers in close but non-contacting relation with each of said domes; means embodying springs to support said strikers, said last-named means being attached to said gudgeon; means on said rotatable member adapted to pass between said domes and said strikers to move the latter inwardly in succession and to release the same; said member being the form of a perforated plate and said first means comprising a pinion in engagement with said plate, and a shaft passed through a hole in said first sounding dome at about right angles to said gudgeon, said shaft being rotatably carried by said support and carrying said pinion within said first dome and said frictional roller externally of said dome.

2. A cycle bell comprising a support; a gudgeon fixed on said support; a first sounding dome fixed to said support co-axially to said gudgeon, said dome opening opposite to said support and being provided with a lateral hole; a plate rotatably mounted on said gudgeon within said dome, said plate being formed with a co-axial circular row of perforations; means on said gudgeon to form a hub for said plate; a toothed pinion in mesh with the perforations of said plate; a shaft at about right angles to said gudgeon to carry said pinion, said shaft extending through the hole of said dome; means carried by said support to rotat-

ably support said shaft; a frictional roller carried by said shaft, said roller being adapted to bear against the tyre of a cycle wheel; a second sounding dome carried by said gudgeon in co-axial but opposed relation to said first dome; a two-armed member fixed on said gudgeon within said domes between said plate and said second dome; coil springs at the ends of said two-armed members, said springs being in substantial parallel relation to said gudgeon; strikers carried by said coil 10 springs in close but non-contacting relation to each of said domes; and a projection on said plate to move said strikers inwardly in succession and to release the same.
